UNITED STATES PATENT OFFICE

MAX BONNAT, OF LYON, FRANCE

CENTRIFUGAL SWITCH

Application filed April 1, 1927, Serial No. 180,290, and in France September 18, 1926.

This invention relates to an improved switch of the type in which a rotating body is formed with a plurality of passages, each containing a ball or roller. The rotation of the aforesaid body will tend to keep these balls out of circuit-closing position in their passages, due to the centrifugal force exerted on them at such time; but when the rotating body slows down to a sufficient extent, then 5 one or more of the balls, according to the position of their carrier body, will travel inwardly far enough to bridge contact between two spaced conducting members, and an electric circuit will be closed wherein an audible 10 or other signal is included.

The present invention resides primarily in the construction of the aforementioned rotating body; its object being to simplify and improve that element and, in particular, to 20 cheapen its cost of manufacture, without in any way decreasing its efficiency. According to the invention, the rotating body takes the form of a cage which consists solely of two metal parts or members riveted together, one 25 member providing the ball passages, which are merely stamped-out channels, while the other member is a simple, flat plate; the first-named or channel member being insulated by a rubber or other non-conducting washer 30 from its carrier spindle. Due to this construction, the use of a solid or other block of insulating material, in which the ball channels have to be formed individually and with considerable care, and which is always more 35 or less fragile, is entirely avoided, the only insulation required being the rubber washer which is directly interposed between the channel member and the spindle. Furthermore, the channels themselves need not be 40 specially curved so as to maintain the balls actually at their outer ends during normal rotation of the cage; but, on the contrary, they serve merely to retard the inward movement of the balls and may, therefore, be arranged radially and along straight lines, 45

though, if preferred, they can be formed with pockets at their outer ends which may extend laterally in either or both directions.

The present switch mechanism is specially applicable to yarn winding or unwinding machinery for the purpose of automatically signalling the breaking of the thread or yarn, and in which it provides a support for the bobbin, spool or other element whereon the bobbin is being wound, or from which it is 50 being unwound; but it is to be understood that other uses of the application are possible.

In the accompanying drawing:

Figure 1 is a part-sectional side elevation 60 of the improved switch and its mounting;

Fig. 2 is a vertical section through the channel member of the ball cage;

Figs. 3 and 4 are views similar to Fig. 2, but showing pocketed channels.

As represented in the drawing, the switch comprises two main members, the ball cage and its carrier spindle. The spindle itself is composed of two metallic members 1 and 2 which jointly support the ball cage at their 70 mutually-adjacent inner ends. This cage consists simply of two metal members 3 and 4, of which the member 3 is merely a flat circular plate or disk, while the member 4 is provided with a set of channels 5 of semi-circular section which are stamped or pressed out from the metal of the otherwise flat plate. These two members are arranged face to face and fastened directly together by rivets 7, and the channel member or plate 4 is preferably formed with a marginal flange or rim 8 which extends across the edge of plate 3 and fits against the same.

In their simplest form, shown in Figs. 1 and 2, the channels 5 are disposed radially of plate 4 along straight or substantially straight lines and at equiangular distances apart; and there is preferably an even number of them (four, in the present instance), so that the effect is the same as if half the number of 85 90

diametric channels were employed. If desired, however, each channel may be provided at its outer end with a lateral pocket 6 which may be single (Fig. 3) or double (Fig. 4) according as rotation of the switch is to take place in one direction only or in either direction alternatively, as indicated by the arrows.

The cage is designed to house a set of balls or rollers 9, one for each channel, made of brass or other suitable metal, which are utilized to close an electric circuit wherein the warning signal (not shown) is included, by bringing the gap between the inner ends 10 of the spindle members 1 and 2, which ends are preferably reduced or pointed. Such circuit, as will be understood, must be kept open under normal running conditions; and to effect this, a washer 10 is interposed 15 between the hub of the channel plate 4 and the spindle member 1, so that current will pass from one spindle member to the other when, and only when, one of the balls contacts with the reduced ends or terminals 20 of both members. It is to be observed that the several channels meet at their inner ends at the center of plate 4, at which point the spindle member passes through said plate and projects for a slight distance into the cage, 25 and that the other spindle member 2 in like manner passes through the center of plate 3 and slightly into the cage.

As has already been stated, the spindle 1-2 of the switch device is designed to carry a 30 spool or bobbin whereon the thread is to be wound or from which it is to be unwound; such operations entailing, in one instance, the application of a positive driving force to the spindle to rotate it and, hence, the spool, and 35 in the other instance, the rotation of the spool by the unwinding thread and, consequently, the rotation of the spindle by the spool. Any suitable mounting for the device may, of course, be provided, as for instance that represented in Fig. 1, wherein 11 and 12 designate metal supports to which the two wires 40 13 and 14 are connected having bearing openings to receive the outer ends of the spindle members. To retain the spool in place upon the spindle, the member 1 thereof may carry 45 one or more spring clips 15 which frictionally engage the bore of the spool.

In operation, the rotation of the spindle and cage incidental to the winding or unwinding of the thread sets up a centrifugal force which is exerted upon the balls 9 in opposition to their normal inward or gravitational movement in their respective channels toward the center of the cage or, in other words, to 50 toward the confronting inner ends of the spindle members. As the speed of rotation increases, the balls tend to move outward and, if a high enough speed is attained, to assume and maintain a position at the outer ends of 55 the channels; but upon a decrease in speed,

the retarding action created by centrifugal force likewise decreases and the centripetal or gravitational force will tend to prevail, with the result that the balls move inwardly toward circuit-closing position and ultimately 60 reach that position when the speed falls low enough. Hence, at one extreme of speed the balls will be kept in the outer ends of the channels, while at the other extreme the signal circuit will be closed. Between these two 65 extremes, the balls will travel outwardly or inwardly in their channels in one direction or the other, according as the speed increases or decreases.

When the pocketed channels are utilized, 70 the operation is substantially the same as before, excepting that the balls will remain in the pockets during much lower speeds than would be possible with straight channels. In 75 the case of the single pockets, shown in Fig. 3, which extend on one side only of the channels, the cage is intended to be rotated in one direction only (counterclockwise, in the arrangement illustrated); but where double 80 pockets are employed, which extend on both 85 sides of the channels (Fig. 4), the cage can 90 operate for either counterclockwise or clockwise rotation.

I claim as my invention:—

1. A centrifugal switch, comprising a rotary current-collecting spindle embodying two structurally-separate sections having a gap between their mutually-adjacent inner ends; a cage supported jointly by the two spindle sections and consisting of two thin, 100 metal disks fastened together face to face and mounted one on one section and the other on the other section, a single one of said disks having a series of radial channels stamped out from it which meet at their 105 inner ends at said gap so as to enclose the latter within the cage; a conducting roller disposed in each channel to travel in opposite directions therein according to speed variations and to bridge the gap when the speed 110 falls below a certain value; and an insulating washer interposed between the hub of the channeled disk and the corresponding spindle section to prevent the passage of current between that section and the other section until the gap is bridged.

2. A centrifugal switch, comprising a rotary current-collecting spindle embodying two structurally-separate sections having a gap between their mutually-adjacent inner ends; a cage supported jointly by the two spindle sections and consisting of two thin, metal disks fastened together face to face and mounted one on one section and the other on the other section, a single one of said disks having a series of radial channels stamped out from it which meet at their inner ends at said gap so as to enclose the latter within the cage, each channel having a laterally-extending pocket at its outer end; a conduct- 125 130

ing roller disposed in each channel to travel in opposite directions therein according to speed variations so as to bridge the gap when the speed falls below a certain value and to
5 enter the respective pocket when it becomes sufficiently high; and means for insulating the channeled disk from the corresponding spindle section to prevent the passage of current between that section and the other section
10 until the gap is bridged.

3. A centrifugal switch, according to claim 2, in which the roller-receiving pockets project laterally from both sides of the channels.

In testimony whereof I affix my signature,
15

MAX BONNAT.
